SOLDERLESS CONNECTOR

John G. Jackson, Detroit, Mich., assignor to
Square D Company, Detroit, Mich., a corpora-
tion of Michigan

Application November 3, 1938, Serial No. 238,605

7 Claims. (CL 173—259)

This invention relates to connectors for electrical conductors and has for its object the provision of an improved, simple and economical form of connector of the solderless type.

Another object of the invention is to provide a simple and economical solderless connector adapted to receive a large variety of sizes of wires.

Another object of the invention is to provide a solderless connection in which the movement 10 of the clamping stud produces a conductor clamping force in a direction traverse to the axis of said stud as well as a clamping force in a direction parallel to said axis.

Another object of the invention is to provide a solderless connector comprising a single formed strip and a force applying means and being of economical construction while effecting a very efficient electrical and mechanical connection.

Another object of the invention is to provide a solderless connector adapted to lock its cooperating clamping stud so as to prevent accidental rotation of the stud and loosening of the connection.

Figure 1 is a transverse sectional view of the connector with a relatively large cable clamped therein.

Figure 2 is a perspective view of the connector of Figure 1.

Figure 3 is a perspective view of an unattached connector element without its clamping stud.

Figure 4 is a transverse sectional view of the connector carrying a relatively small wire.

Figure 5 is a perspective view of connector of Figure 4.

The connector 1, as illustrated in the drawing, is formed of a single length conducting strap return bent upon itself, and having a longitudinally extending slot 2 therein; the slot 2 being provided with generally circular extremities 3 and 4, each of whose diameters exceed the width of the slot proper.

The connector is provided with a side 5 rounded outwardly and with a side 6 tilted inwardly, and having outwardly directed flanges 7 thereon to provide rigidness to said side and to prevent its buckling beneath an applied clamping force. An abutment portion 8 is formed out of base 9 of the connector and is directed upwardly therefrom to engage the tilted side 6. The circular extremity 3 of slot 2 cooperates with an opening 11 in the base 9 to receive a washer head stud 10 having a diameter greater than the width of slot 2. With the insertion of a cable terminal end and tightening of the clamping stud 10, as depicted in Figures 1 and 2, the connected end

of tilted side 6 will be forced to the right drawing the top wall 12 of the connector in the same direction and in a generally horizontal plane, the connector strap bending principally adjacent the circular extremity 4 of the slot 2 where there is the least metallic width and consequently a local weakening. As the stud 10 has a diameter greater than the width of slot 2, this movement of the top wall 12 will force the edges of slot 2 into tight engagement with the stud to produce a locking effect preventing accidental loosening of the stud. The movement of the top wall 12 will further cause the rounded side 5 to bear upon the cable terminal end and force it against stud 10, thus securing a clamping pressure in a direction 13 transverse to the axis of stud 10 as well as the clamping pressure parallel thereto by the direct clamping of the cable between the base 9 and the top wall 12.

With the substitution of cable terminal ends of 20 extremely small diameter as shown in Figures 4 and 5, the horizontal movement of the top surface has little effect upon the cable end 13 therein. The cable being secured within the connector entirely by the direct clamping pressure between 25 the base 9 and top wall 12.

Rotation of connector 1 may be prevented by the engagement thereof with a stationary part on the device on which it is mounted and in the drawing one manner of accomplishing this result has been shown wherein an upturned lug 14 on a terminal plate 15 carried by an insulating portion 16 of a switch or other electrical device is received within the extremity 4 of slot 2 and prevents rotation of the connector with respect to 30 plate 15 and other parts of the device.

While certain preferred embodiments of the invention have been specifically disclosed, it is understood that the invention is not limited thereto as many variations will be readily apparent to those skilled in the art and the invention is to be given its broadest possible interpretation within the terms of the following claims.

I claim:

1. An electrical connector of the solderless type 45 comprising a continuous strap return bent upon itself to form a loop having substantially generally parallel top and bottom portions and opposite side walls, one of said side walls being rounded outwardly and the other side wall tilting inwardly, the top wall being provided with an elongated opening therein and a clamping means passing through said elongated opening and an opening in the bottom wall of the connector, said 50 clamping means having a force applying surface 55

- located directly above at least a part of a conductor inserted in said connector between said rounded side and said clamping means, the top wall of the connector moving transversely to the axis of the clamping means under the action of the clamping thereof, whereby said rounded side forces said conductor against said clamping means to apply a transverse clamping pressure thereto in addition to the direct clamping pressure applied beneath said force applying surface.
2. An electrical connector of the solderless type comprising a continuous strap return bent upon itself to form a closed loop having substantially flat generally parallel top and bottom walls and opposite side walls, said top wall having an elongated opening therein, clamping means passing through said elongated opening in the top wall and through an opening in the bottom wall, one of said side walls being so disposed with respect to said clamping means as to provide a space therebetween for the reception of a conductor to be connected, the side opposite said first mentioned side being tilted inwardly and being provided with side flanges to impart rigidity thereto, said top wall moving transversely to the axis of the clamping means under the clamping action thereof, whereby said first mentioned side forces the conductor against the clamping means to apply a transverse clamping pressure thereto in addition to the clamping pressure applied between the top and bottom walls.
3. An electrical connector of the solderless type comprising a continuous strap return bent upon itself to form a closed loop having substantially flat generally parallel top and bottom walls, and opposite side walls, said strap having a continuous elongated opening therein extending from the top wall to the bottom wall thereof, one side of said connector being tilted inwardly, clamping means passing through said elongated opening in the top and bottom walls of the connector, the side of said connector opposite said one side being spaced from the clamping means to provide for the reception of a conductor therebetween, the clamping force of said clamping means causing said one side to be further tilted as the top wall is moved toward the bottom wall in the clamping action, said further tilting causing a consequent movement of the top wall at right angles to the axis of the clamping means whereby said opposite side forces the conductor against the clamping means to apply a transverse clamping pressure in addition to the direct clamping pressure applied by said clamping means.
4. The connector defined in claim 3 in which the width of said elongated opening is less than the diameter of the clamping means, whereby the side edges of the opening engage the clamping means to produce locking effect thereupon.
5. An electrical connector of the solderless type comprising a continuous strap return bent upon itself to form a closed structure having substantially flat generally parallel top and bottom walls and opposite side walls, clamping means passing through the spaced top and bottom walls of the connector and threaded into a stationary conducting part against which the bottom wall is disposed, the space between said clamping means and one side of the connector serving for reception for the conductor to be connected, said clamping means including a force applying surface located directly above said conductor receiving space whereby said clamping means exerts a direct clamping pressure on said conductor between said top and bottom walls, and means including an elongated slot in said strap through which the clamping means extends for bodily moving said side wall under the force applying action of said clamping means to apply a transverse clamping pressure thereto in addition to the direct clamping pressure between the top and bottom walls.
6. An electrical connector of the solderless type comprising a body member having a tilted side and an opposite side rounded outwardly, an elongated slot in said member, clamping means passing through said slot and threaded into a stationary conducting part and positioned to provide a space between the rounded side and the clamping means for the reception of a conductor to be connected, said clamping means including a force applying portion disposed directly above said conductor receiving space to apply a direct clamping pressure on said conductor, said clamping means cooperating with said tilting side to move said rounded side transversely to force said conductor against clamping means to apply a transverse clamping pressure thereto, in addition to the direct clamping pressure exerted by said force applying portion.
7. An electrical connector of the solderless type having a body member, an elongated opening therein, and having a tilted side and a side opposite thereto rounded outwardly, clamping means extending through said elongated opening and positioned to provide a space between the clamping means and said rounded side for the reception of a conductor to be connected, said clamping means including a force applying portion located directly above said conductor receiving space, said tilted side cooperating with said clamping means under the clamping action thereof to move said rounded side to urge the cable terminal end against the clamping means to thereby apply a transverse clamping pressure to the conductor in addition to the direct pressure exerted by the clamping means parallel to its axis.
